ELECTRICAL MUSICAL INSTRUMENT

John M. Hanert, Wilmette, Ill., assignor to Hammond Instrument Company, Chicago, Ill., a corporation of Delaware

Application October 14, 1940, Serial No. 361,065

25 Claims. (Cl. 84—1.11)

My invention relates generally to electrical musical instruments, and more particularly to melody instruments of this character.

It is an object of my invention to provide an improved melody type electrical musical instrument in which the player may readily control the application of a vibrato to any particular note or notes in the course of playing a musical selection.

A further object is to provide an improved electrical musical instrument of the melody type in which the amplifier output is controlled by the operation of the generator.

A further object is the provision in an electrical musical instrument of the melody type, of a simplified key circuit whereby the closure of a single switch by the key results in excitation and tuning of the generator, and as an incident thereto controlling the acoustic envelope of the tone produced.

A further object is to provide an improved electrical musical instrument having a keyboard employing a double touch, in which the second touch controls the application of a vibrato to the tones produced.

A further object is to provide a melody instrument keyboard in which circuits through a single contact operate to excite and tune the generator, and to render an amplifier effective in the transmission of the signal to a loud speaker.

A further object is to provide a simplified circuit arrangement in which a key operated switch is connected to an oscillator tuning circuit, and also to a D. C. network for removing an amplifier cutoff bias whenever one of the playing keys is depressed.

A further object is to provide relaxation means to render the decay envelope substantially transientless upon the release of a playing key.

A further object is to provide an improved electrical musical instrument of the melody type in which the control tubes operate at low potentials thereby reducing sparking.

A further object is to provide an improved varying permeability tuned vibrato apparatus.

A further object is to provide a simple electrical musical instrument of the melody type which may be economically manufactured and which will be capable of use for the rendition of simple melodies in a musically interesting and artistic manner.

Other objects will appear from the following description, reference being had to the accompanying drawings in which:

Figure 1 is a circuit diagram of a complete instrument, except for the power supply system;

Figure 2 is a circuit diagram of a modified form of the invention; and

Figure 3 is a somewhat diagrammatic view of an exemplary key and switches operated thereby.

General description

The instrument comprises generally an oscillator which is tuned to the semitone note frequencies by a plurality of condensers which are connected into the tuning circuit of the oscillator by the operation of the keys. In the particular embodiment shown herein, the instrument is assumed to have three octaves of keys, and a three octave pitch register which may be of the range from the note C3 (261.626 C. P. S.) to the note C6 (2093 C. P. S.).

Each of the keys operates a switch which determines the frequency of oscillation of the oscillator, and in addition operates a switch which determines whether or not the vibrato should be present in the generator signal.

In one form of the invention the oscillator is normally non-oscillating and is rendered operative by the closure of the key operated switch, and only after the oscillator has been rendered operative is the output thereof connected to the output circuit of the instrument. In another form of the invention the operation of the tuning contact itself by the key results in rendering a pair of control tubes effective to transmit the signal. This is accomplished through a delay circuit so that the oscillator will have attained a stable oscillation condition before the signal therefrom is transmitted through the control tubes.

The instrument is of the melody type and embodied in the same general form and playable in the same general manner as the instrument disclosed in the patent to Laurens Hammond No. 2,203,569, or the keyboard and tone cabinet may be combined to form a unitary structure and used as a solo instrument.

The master oscillator is provided with means for introducing a vibrato and this means is controlled by a second touch contact under each of the playing keys. Thus, the vibrato effect may be introduced at will by the player merely by pressing harder on the playing keys.

Intermediate the master oscillator and the output circuit is a relaxation apparatus which is effective to transmit a signal from the master oscillator to the output circuit only when the master oscillator is operating. Associated with the output of this relaxation apparatus and controlled by the output of the latter is a relay controlled switch mechanism and associated circuit by which the operation of the amplifier is controlled. The output circuit of the instrument includes tone controlling meshes and the amplified output is supplied to a speaker.

Master oscillator and key controlled tuning circuits

The master oscillator comprises a tube VI, preferably a remote cutoff pentode of the 6EY6C

type. The cathode of V_1 is connected to ground and its control grid is self-biased through a resistor R_1 in shunt with a condenser C_1 , and is connected to ground through an inductance L_1 of an oscillation transformer T_1 . The screen grid of V_1 is connected to a +250 v. terminal of the power supply system through a voltage dropping resistor R_2 , and screen degeneration is reduced by means of condenser C_2 . The plate of V_1 is connected through a load resistor R_3 in series with a feed-back winding L_2 of oscillation transformer T_1 , and through a signal resistor R_4 to a +250 v. terminal on the power supply system.

The phasing of L_2 relative to L_1 is such as to produce self-oscillation. The frequency of oscillation is determined principally by the inductance of L_1 and the capacity connected between a conductor 10 and ground.

There are three octaves of keys plus a semi-tone, the keys being designated C_3 to C_6 inclusive for notes of frequencies from 261.626 to 2093 C. P. S.

As shown in Figure 3, each of the keys, for example key C_3 , is adapted sequentially to open a switch 14 and close a switch 16 . The switch 14 comprises an upper rigid contact arm 18 and a lower resilient flexible contact arm 20 , both of these arms being suitably mounted in an insulating supporting structure 22 . The switch 16 comprises a relatively strong resilient and flexible arm 24 having a contact adapted to engage a bus bar 26 which is connected to ground. The key may have formed thereon or suitably operated thereby an actuator 28 of insulating material which engages the switch arm 20 , and upon initial movement of the key opens the switch 14 .

The switch arm 20 has an insulating projection 30 formed thereon which, after the switch arm 20 has been flexed a sufficient distance, engages the switch arm 24 . The switch arm 24 is sufficiently stiff so that the player in depressing the key will feel a distinct stopping effect to the downward motion of the key, and will find it necessary consciously to exert additional pressure in order to cause the switch arm 24 to flex downwardly sufficiently to close the switch 16 . In this way the musician may readily control by his finger pressure whether switch 14 alone should be operated, or whether both the switch 14 should be opened and the switch 16 closed.

Referring to Figure 1, it will be noted that the switches 14 for all of the keys are connected in series, and that the switch arm 20 of each of these keys is connected to one of a plurality of tuning condensers C_8 , each of the condensers C_8 having one terminal thereof connected to the common conductor 10 .

It will be noted that the switch 14 for the key C_3 has its switch arm 18 connected to the conductor 10 through a resistor R_5 which is provided to introduce sufficient resistive impedance in shunt with the tuning circuit of the oscillator to cause the latter to cease oscillation when all switches 14 are closed. The condenser C_8 associated with the key C_6 , the highest key of the keyboard, is permanently connected between the conductor 10 and ground. It will thus be seen that the operation of any of the playing keys will result in the connection of all of the condensers C_8 to the right (Fig. 1) of the key being connected between the conductor 10 and ground, and thus in shunt with the inductance L_1 , determining the resonant frequency, or frequency

of oscillation, of the master oscillator. All of the condensers C_8 to the left of the key depressed will of course be disconnected from the circuit, and it will thus be seen that if two or more keys are simultaneously depressed, the highest of the depressed keys will determine the frequency of the master oscillator.

Vibrato Apparatus

A tap 32 on the oscillation transformer T_1 is provided as part of means to vary inductance of the winding L_1 periodically at a vibrato frequency. The means for accomplishing this comprising a vibratory reed 34 which is connected to ground at its fixed end and at its free end carries an iron core 36 , the mass of which relative to the stiffness of the reed 34 is such as to cause the latter to have a natural frequency of vibration of approximately 7 C. P. S. The core 36 is preferably made of powdered iron molded in shape by the use of a suitable insulating binder, and moves into and out of the field of a coil L_3 , one terminal of which is grounded and the other terminal of which is connected to a tap 38 of an inductance L_4 .

A pair of switches 40 and 41 is connected together for simultaneous manual operation, the arrangement being such that the switches are alternately closed in such manner that both switches are never closed at the same time. When the switch 40 is closed and the switch 41 is open, as the switches are illustrated in full lines in Fig. 1, one terminal of the coil L_3 is connected directly to the ungrounded terminal of the coil L_4 , and the coil L_4 is thus completely disconnected from the circuit so as to have no effect upon the operation. The degree of frequency shift is then dependent upon the change of inductance of L_4 as the iron core 36 vibrates in its field. Because the core 36 is preferably made of a powdered iron in which the particles are suitably insulated from one another and bound together, the core losses for the inductance L_3 are reduced to an extremely low value. The amount of vibrato of course will also depend upon the position of the tap 32 on the inductance L_1 .

When the switch 40 is open and the switch 41 closed, as indicated in dotted lines in Fig. 1, the ungrounded terminal of L_3 is connected to the tap 38 on L_4 . The tapped inductance L_4 then functions as an autotransformer to reduce the effectiveness of the variable inductance L_3 in producing variations in the tuning inductance L_1 . Thus, the degree of vibrato is reduced. However, the average inductance (likewise the frequency of the master oscillator) looking out of the tap 32 of the winding L_1 , is the same whether the switches $40, 41$ are in their full line vibrato "on" position, or whether these switches are in their dotted line vibrato "off" position. This is because of the added shunt inductance L_4 . In effect, the shunt inductance of L_4 , which of course is not variable, compensates for the loss in effectiveness of the variable inductance L_3 when the vibrato switches $40, 41$ are turned off. The position of the tap 38 , together with the inductance of L_4 , determines the degree of residual vibrato present when the switches $40, 41$ are in "off" position. It is of course desirable to have at least a small amount of vibrato present in the tones when rendering substantially all musical selections.

The vibrato reed may be driven by any suitable means such as for example that shown in the patent to Laurens Hammond No. 2,126,682 or in the co-pending application of Laurens Ham-

mond, Serial No. 362,018, filed October 21, 1940, now Patent No. 2,251,052, granted July 29, 1941.

The switches 40, 41 are actuated by the armature of a relay winding 39, one terminal of which is connected to a suitable voltage source such as a terminal +20 v. of the power supply system, and the other terminal of which is connected through a normally closed switch 43 to a conductor 42, the latter being connected to the contact switch arms 24 of all of the switches 16. It will thus be seen that whenever a key is depressed to a sufficient extent to close its switch 16, the relay 40 will be energized to cause the switch 40 to close and the switch 41 to open, thus rendering the vibrato apparatus fully effective to produce a wide vibrato effect in the frequency of oscillation of the master oscillator.

Upon such occasions when the player does not desire the wide vibrato effect throughout the rendition of a complete selection, or a substantial portion thereof, the vibrato second touch may be rendered ineffective by manually opening the switch 43. Conversely, if the player desires the vibrato continuously, without necessitating full depression of the playing keys, a switch 45 may be manually closed to complete an energizing circuit for relay winding 39, thus maintaining the switches 40, 41 in vibrato "on" position until the switch 45 is opened.

Master oscillator wave shape distorter

The master oscillator produces a signal whose quality is not particularly desirable musically, and means are therefore provided to change the wave shape of this output signal to a form in which there is high harmonic development. This means comprises a tube V2 which may be a triode of the 6J5G type, the grid of which is connected through a condenser C10, a feedback winding L5, and a protective resistor R6, to the output of the master oscillator tube V1, bias being provided through a grid return resistor R7 connected to a suitable source of negative grid bias of the power supply system.

The plate of tube V2 is connected through a charging resistor R8 to a +250 v. terminal of the power supply system, and is also connected to ground through a timing condenser C11 and the primary winding L6 of the transformer T2, the winding L6 being shunted by a load resistor R9. The cathode of the tube V2 is connected to ground. The tube V2 together with its associated circuits constitutes a relaxation oscillator which is normally prevented from oscillating by the high negative bias impressed on the grid of the tube V2 through the resistor R7. However, upon positive pulses of the signal transmitted through the condenser C10, the bias is reduced sufficiently to permit discharge of the condenser C11 through the tube. This discharge through the tube causes current to flow through the primary winding L6 of transformer T2. This pulse of current through the primary winding L6 induces a corresponding pulse in the secondary winding L5 of transformer T2 in a direction tending to increase the bias on the grid to its cutoff value.

When tube V2 is cut off, condenser C11 again is charged at a rate determined by the timing constant of R8 relative to C11 and this results in producing current flow in the primary winding L6 which of course reflected in the winding L5, in a direction to decrease the bias on the grid of the tube V2. This operation continues until the bias is sufficiently small so that the signal

from the master oscillator transmitted through the condenser C10 is again effective to trip the tube V2.

When no signal is being supplied to the grid 5 of the tube V2 through the condenser C10, i. e., when the master oscillator is not in operation, the bias on the tube V2 is never reduced sufficiently to permit plate current flow. This prevents self-oscillation from occurring when the master oscillator is not in operation.

Furthermore, it will be noted that while the tube V2 is tripped by the signal from the master oscillator, it continues a complete cycle of relaxation after being tripped irrespective of 15 whether or not the master oscillator stops oscillating. Thus, transients due to the stopping of oscillations of the master oscillator do not appear to any appreciable extent in the output of the tube V2.

Tone envelope control circuits

A tertiary winding L7 of the transformer T2 has its terminals connected to the grid of control tubes V3 and V4 respectively, and has a center tap 44 connected through a bias controlling circuit by which the attack and volume may be controlled. The plate of tubes V3 and V4 are connected to a +250 v. terminal of the power supply system through resistors R11 and R12 respectively. The suppressors of tubes V3 and V4 are connected to ground and the screens are connected to a +100 v. terminal of the power supply system. The amplitude of the output signal from the tubes V3 and V4 is determined by their grid bias, these tubes preferably being remote cutoff pentodes, such as the 6K7G type.

The bias upon the tubes V3 and V4 is controlled through a circuit comprising a volume control mesh consisting of a variable volume controlling resistor R13 which is connected across a 50 volt source of potential indicated by a battery 46, a protective resistor R14 being connected in series with the battery 46. A decoupling resistor R15 is connected between the resistor R13 and the center tap 44 and the resistors R13 and R15 are shunted by a condenser C12. The resistor R15 and condenser C12 serve to prevent the potential at the terminal 44 from changing rapidly with changes in the resistance R13. By 40 using this condenser C12 and resistor R15 in conjunction with the variable resistor R13, the latter may be made in a simple and economical form comprising a plurality of fixed resistors which may be successively connected in parallel.

45 The resistors R13 and R14 are connected by a conductor 47 with a terminal 48 which is connected to ground through a condenser C13. The terminal 48 is connected through a normally closed switch 50 and a damper resistor R16 to a terminal 52 of the power supply system which is at cutoff potential for the tubes V3 and V4. The terminal 48 is connected through a decay resistor R17 to a switch arm 54 which is adapted to make contact selectively with any one of three terminals, -50 v., -15 v., and 3 v. of the power supply system.

50 A switch arm 56 is adapted to make contact either with a contact 57 or a contact 58, the switch arm being connected to ground through a condenser C14. An attack resistor R18 connects the contact 58 with the terminal 48, while an anti-spark resistance R19 connects the contact 57 with a switch arm 60 which may be operated selectively to make contact with any one of three terminals -50 v., -3 v., or +50 v.

of the power supply system. The resistor R18 inhibits sparking at the contacts upon making and breaking the circuit between 56 and 58.

The switch arms 50 and 56 form parts of a relay having a winding 62, one end of which is connected to a terminal +250 v. of the power supply system and the other terminal of which is connected to the plate of a tube V5, the winding 62 being shunted by a condenser C15 of such size as to provide a direct current reservoir of electrical energy to prevent "chattering" of the relay contacts. When this relay is energized the switch arms 50 and 56 are moved from their full line positions to their dotted line positions (Fig. 1).

The grid of the tube V5 is connected to a fourth winding L8 of the transformer T2, the other end of the winding being connected to a terminal 64 of the power supply system providing cut-off bias for the tube V5 when no signal is present on its grid. The tube V5 may be a triode of the 6J5G type. Thus, the tube V5 is non-conducting unless a signal is being provided by the output of the tube V2. When such signal is provided a D. C. voltage builds up across the condenser C5 causing relay 62 to be energized, thereby first to open switch 50 and break the contact between switch arm 56 and contact 57 and thereafter make a contact between switch arm 56 and contact 58.

Output circuit

The output of the two control tubes V3 and V4 is transmitted through blocking condensers C17 and C18. The output transmitted through the condensers C17 and C18 may be modified by suitable tone controlling resonant circuits bearing the legends "Deep tone," "Full tone," "First voice," "Second voice," and "Brilliant tone," the signal, as thus modified by the tone controls, being amplified by the power amplifier tubes V7 and V8 which may be of any suitable type such as 6F6G pentodes. The output of the tubes V7 and V8 is coupled to the voice coil of a speaker 66 through an output transformer T3.

Modification shown in Fig. 2

In Fig. 2 I have illustrated a modified form of my invention in which a number of parts have been eliminated and which may therefore be more economically manufactured. The form of the invention shown in Fig. 2 is capable of producing many interesting musical results, but is not as versatile in the possible variations in tone envelopes as the previously described apparatus. Since most of the parts of the circuit shown in Fig. 2 are identical to those shown in Fig. 1 and above described, the reference characters used in connection with the description of Fig. 1 have been applied to the corresponding parts shown in Fig. 2 and will not again be enumerated.

Each of the keys C3 to C6 inclusive is adapted upon depression to close a switch 70, and upon further depression against a mechanical resistance to close the vibrato control 16 as described with reference to Figs. 1 and 3. The conductor 10 forming the tuning connection to the master oscillator is connected by a condenser C19 to a series of tuning condensers C20.

A resistor R20 is shunted around each of the condensers C20 and the resistors R20 are thus connected in series. The resistors R20 constitute part of a D. C. voltage divider system to be explained hereinafter, but are of impedances 75

sufficiently high so as not seriously to degenerate the "Q" of the master oscillator tuning system. The condenser C19 is a tuning condenser and determines the resonant frequency of the tuning circuit for the master oscillator when the key C3 is depressed. Because of the series connection of the condensers C19 and C20, the lowest of several simultaneously depressed keys will determine the resonant frequency of the tuning circuit of the master oscillator, since all of the switches 70 make contact with a grounded conductor 71.

It will be noted that when none of the keys is depressed, the master oscillator would have a tendency to oscillate at a radio frequency due to 15 the distributed capacity in the inductance L1 and in the conductors connected therewith, and to prevent this, a condenser C21 of very low value is connected between the plate of the tube V1 and ground. This condenser forms an effective 20 by-pass for high frequency and prevents effective energization of the feed-back inductance L2.

The resistors R20, as previously indicated, form part of a voltage divider system which includes a resistor R21 connected to a terminal 72 at approximately the mid-point of the series of resistors R20, the other end of the resistor R21 being connected to a terminal 74, and the latter is connected to a terminal -101 v. of the power supply system through a resistor R22. The resistor R21 may have a value of 7 megohms, while the resistor R22 has a value of 1.42 megohms, the resistors R20 being of value small relative to the values of the resistors R21 and R22 so that the potential on terminal 74 will be substantially 35 the same irrespective of which of the keys is depressed.

The terminal 74 is connected to the terminal 48 through a decoupling resistor R23 and the terminal 48 is connected to ground through a 40 condenser C22. A second condenser C23 is adapted to be connected in shunt with the condensers C22 upon closure of a switch 76. When the switch 76 is open, due to the condenser C22, the potential at the point 48 is prevented, to a 45 limited extent, from suddenly changing at the same rate as does the potential at the point 74. When the switch 76 is closed, due to the additional capacity of C23, the potential on the terminal 48 will rise at a very slow rate relative to 50 the potential change on the terminal 74, thus to provide a musically desirable slow tonal attack.

The tubes V3 and V4 in Fig. 2 are operated with their plates connected to ground through the resistors R11 and R12, and with their screens 55 connected to a terminal -50 v. of the power supply system and their cathodes connected to a terminal -83 v. of the power supply system. It is thus seen that the plate voltage on these tubes is only 83 volts positive and that their screen 60 voltage is only 33 volts positive with respect to the cathode. Also, the volume control battery 46 is of lower voltage indicated as -17 v. With these voltages, the amplification of tubes V3 and V4, as shown in Fig. 2, is considerably less than 65 that shown in Fig. 1. In order to compensate for this reduction in amplification, an additional pair of push-pull amplifier triodes V9 and V10 (preferably of the 6J5G type) are inserted between the output circuits of tubes V3 and V4, and 70 the input of the power amplifier tubes V7 and V8. By operating tubes V3 and V4 at low potentials, the voltages attained by the tuning condensers C20 are made correspondingly smaller than if the tubes V3 and V4 were operated under 75 their normal rated voltages, thereby decreasing

the sparking across the contacts of the switches 70 as the latter are operated.

Thus, when the tuning switches 70 are open, which is the normal case when the instrument is not producing a sound, the potential at the terminal 74, as well as at terminal 48, is -101 v. The actual bias applied to the control grids of tubes V3 and V4 may be 17 volts more negative, namely, -118 volts, depending of course upon the adjusted position of the expression or swell control variable resistance R13. However, under these conditions, the tubes V3 and V4 will be cut off irrespective of the position of adjustment of the swell control.

When any playing key is depressed, thereby closing one of the switches 70, the potential at the point 74 will rise from -101 volts to -84 volts, causing corresponding increase in the potentials of terminals 48 and 49, and thus removing the cutoff bias on tubes V3 and V4, and rendering them effective to transmit to their output circuit the signal impressed upon their control grids. Thus, the switches 70 are effective, not only to complete the circuit to tune the master oscillator to the desired note frequency, but also to cause transmission of the signal generated by the master oscillator to the output of the instrument.

Operation

The instrument as above described made either in accordance with the disclosure of Fig. 1 or that of Fig. 2, is operated in the manner of a melody instrument, that is, but one key is operated at a time. In playing the instrument, assuming that a suitable power supply system has been energized, let us assume the musician depresses the key C3 until the switch actuator 28 thereof has opened the switch 14, Figs. 1 and 3, or referring to Fig. 2, has closed the switch 70. Such operation will result in tuning the master oscillator to the frequency of the note C3 (261.626 C. P. S.), the exact frequency being determined by adjustment of the inductance L1 (and incidentally also inductance L2), as by varying the amount of iron effectively in the core of L1 and L2.

In the circuit of Fig. 1, the master oscillator being normally rendered non-oscillatory when the tuning circuit is shunted by the resistor R5, is rendered oscillatory as soon as the switch C3 is depressed to open the switch 14. The master oscillator thus commences supplying the signal to the tube V2 and hence to the windings of the transformer T2. The resulting signal in winding L8, through the rectification of the tube V5, causes energization of the relay winding 62. Energization of this relay opens switch 50 and swings switch arm 56 from the contact 57 into engagement with contact 58.

Depending somewhat upon the adjustment of the switches 54 and 60, the operation of these switches 50 and 56 will result in raising the control grid bias on the tubes V3 and V4 at a predetermined rate so as to produce a desired rate of attack, and permitting this biasing potential to drop at a predetermined rate to produce the desired decay characteristics in the tone. The signal from the output of the tube V2 is thus transmitted through the tubes V3 and V4 with a controlled amplitude envelope.

Any transients which may be present incidental to the starting of the master oscillator V1 and the relaxation oscillator including the tube V2, will not be transmitted to the output of the instrument because of the fact that the circuit and apparatus determining the grid bias on the tubes

V3 and V4 is not instantaneous in action. Thus, a short interval in the nature of 30 milliseconds is provided, during which time the relay operates and the grid bias changes to a value which renders the tubes V3 and V4 conducting. However, when the key is released, the master oscillator stops oscillating substantially instantaneously. This, however, does not cause instantaneous cessation of operation of the relaxation circuit of the tube V2, since the latter will complete a cycle of relaxation before it ceases operation. Following this cycle the condenser C11 will be charged at a controlled rate through resistor R8 to the potential +250 v. as derived from the power supply system, but this potential is not sufficient to cause the tube V2 to discharge because of the grid bias thereon.

The output of the tubes V3 and V4 is suitably modified at the will of the musician by the tone controls, and the modified signal is further amplified by tubes V7 and V8 and supplied to the speaker 66.

Whenever the player desires to have a vibrato effect in the tones produced, he will exert sufficient pressure on the key to close the switch 16. Closure of this switch will result in energization of the relay 39 and will move switches 40 and 41 from their dotted line positions to their full line positions, thus rendering the vibrato apparatus effective periodically to vary the frequency of oscillation of the master oscillator in the manner previously described.

If the player does not wish to employ the second touch vibrato he may disconnect it by opening the switch 43 in which case the closure of one of the switches 16 will of course not result in energization of the vibration control relay 39. On the other hand, if the player desires to have the vibrato on all tones without requiring the full depression of the keys, he may close the manually operated switch 45 which will result in maintaining the vibrato relay 40 energized.

As previously described, the player may adjust the switches 54 and 60 to predetermine the character of the tone intensity envelope. For slow attack the switch 54 is adjusted to its -3 v. contact, while the switch 60 is adjusted to a -50 v. contact. To attain a percussion tone intensity envelope the switch 54 is adjusted to a -50 v. and the switch 60 is adjusted to a +50 v. To attain a sustained organ-like tone, both switches 54 and 60 are adjusted to their -3 v. contacts. To attain a percussion envelope merging into a sustained tone of constant intensity, the switch 54 is adjusted to its -15 v. contact, while the switch 50 is adjusted to its -3 v. contact.

In the case of a slow attack tonal envelope, the potential on condenser C13 is normally maintained at a cutoff potential 52 through the relatively small resistor R16. Upon depression of a playing key and subsequent operation of relay 62 this cutoff potential is removed through the operation of switch arm 50. The -50 v. potential which is normally on condenser C14 under these conditions of adjustment is, upon movement of the switch arm 56 into engagement with the contact 58, impressed upon junction terminal 48 through a resistor R18 which is of relatively small value; and serves merely to prevent transients. This potential then divides between the condensers C14 and C13. By making the condenser C13 small with respect to condenser C14, substantially the cutoff potential -50 v. is impressed upon the condenser C13 and thus main-

tains the control grids of tubes V3 and V4 initially at cutoff. However, at a time dependent upon the time constant of resistor R17 and condensers C13 and C14, the -3 v. potential, as derived from the switch 54, raises the potential on the junction terminal 48, thus removing the cutoff bias on tubes V3 and V4 and causing the signal to be conducted by these tubes at a gradually increasing amplitude.

When the switches 54 and 60 are set for a percussion tone envelope, the condenser C14 normally has a +50 v. charge thereon which is impressed (with but slight diminution due to the charging of the condenser C13), upon the junction terminal 48, thereby rapidly changing the bias on tubes V3 and V4 to a high value. The charge on the condenser C13 and C14 is then gradually dissipated through the resistor R17 to the -50 v. terminal of the switch 54, until the potential on the grids of the tubes V3 and V4 drops to a cutoff value which will correspond to a potential of -40 v. to -50 v. on the terminal 48.

The relay operated switches 50 and 56, as well as the manually operated switches 54 and 60 and their associated circuits, operate in a similar manner to produce the sustained organ-like tone and the percussion followed by a sustained tone level.

In the simplified form of the keying circuit shown in Fig. 2, a wide variety of tonal intensity envelopes is not available to the player, but the attack may be made slower by closing the switch 76 or the tone envelopes. The simplified form of the instrument as shown in Fig. 2 does not require elaborate intensity envelope controls if the instrument is to be used in conjunction with the piano, which of course produces percussion tones. If the instrument is to be used as a solo instrument, for instance with orchestras, the intensity envelope controls of Fig. 1 are preferably utilized.

In playing the instrument the player may produce many new and interesting musical results, since the notes may be played with or without the vibrato effect, merely by applying increased pressure to the keys whenever the vibrato effect is desired. The various other controls which may be selectively operated by the musician make it possible for him to obtain numerous other musically desirable effects. Despite the great versatility of the instrument, it may be economically produced since it is of relatively simple construction.

While I have herein disclosed preferred embodiments of the invention, it will be apparent to those skilled in the art that numerous variations and modifications may be made without departing from the underlying principles of the invention. In the foregoing description, it will be understood that the values of the circuit elements, the types of tubes employed, and the values of the potentials given are merely exemplary, and may be varied considerably, especially if compensatory changes are made in other components of the apparatus. I therefore desire, by the following claims, to include within the scope of my invention all such variations and modifications of the invention by which substantially the results of the invention may be obtained through the use of substantially the same or equivalent means.

I claim:

1. In an electrical musical instrument having a frequency generating system and an output circuit including an electroacoustic translating means, the combination of a keyboard having a plurality of depressible keys, means operated by said keys when they are depressed a predeter-

mined distance to cause transmission to said output circuit of signals from said generating system, means to impart a resistive force to the further depression of said keys after they have been depressed said predetermined distance, a relay controllable by any one of said keys when depressed beyond said predetermined distance, and means controlled by said relay to cause the introduction of a vibrato effect in the signals produced by said generating system.

2. In an electrical musical instrument having an output circuit including electroacoustic translating means and a variable frequency tone signal generating system, means to vary the frequencies generated by said system to introduce a vibrato effect, a plurality of depressible playing keys selectively operable upon, partial depression to determine the average frequency of said generating system and to control the transmission of signals from said generating system to the output circuit of the instrument, means common to all and controllable by any one of said playing keys when any one of the latter is completely depressed to render said vibrato means effective, and resilient stops for said keys affording greatly increased resistance to depression of said keys as they approach their completely depressed positions.

3. In an electrical musical instrument, the combination of a variable frequency generator, a plurality of playing keys, a tuning switch operable by each of said keys, means controlled by said switches to determine the frequency of operation of said generator, vibrato means to vary the frequency of operation of said generator at a vibrato rate and through a vibrato range, means associated with said keys to impose a pronounced mechanical resistance to their depression beyond the extent necessary to operate their associated tuning switches, and switch and relay means to render said vibrato means effective upon operation of any of said keys appreciably beyond the extent necessary to operate its associated tuning switch.

4. In an electrical musical instrument, the combination of a normally non-operating oscillator, key controlled means to start said oscillator and tune it to a predetermined musical note frequency corresponding to the operated key, a normally non-operating signal transmission control means connected to receive a signal from said oscillator, and means operated by the signal produced by said oscillator to render said signal transmission control means effective to transmit the signal produced by said oscillator, said last named means introducing sufficient delay to prevent the transmission through said signal transmission control means of transients produced incidental to the starting of said oscillator.

5. In an electrical musical instrument, the combination of an oscillator, a playing key, a switch operable by said key, means controlled by said switch to tune said oscillator to a note frequency corresponding to that represented by the key, a device for controlling the output of said oscillator, and means controlled by said switch to render said device effective to transmit the output of said oscillator upon depression of a playing key, said last named means including means for introducing a fractional second delay whereby transients incidental to starting said oscillator will not be transmitted to the output of the instrument.

6. In an electrical musical instrument, a master oscillator, a normally inoperative relaxation

device connected to receive the output of said master oscillator and having its frequency of relaxation controlled thereby, key controlled means to tune said master oscillator to a musical note frequency, an amplifier coupled to the output of said relaxation device, means normally maintaining said amplifier inoperative, and means controlled by the output of said relaxation device to render said amplifier operative whenever said relaxation device operates, said last-named means including a fractional second delay means whereby said amplifier will be rendered gradually effective and its output will be free from undesirable transients produced incidental to starting and tuning said master oscillator.

7. In an electrical musical instrument having a generator of electrical signal impulses; an amplifier for the output of said generator, key controlled means for rendering said generator operative, a circuit connected to said amplifier for controlling the operation thereof, said circuit having a terminal the direct current potential of which determines the degree of amplification of said amplifier, means normally maintaining a potential on said terminal of a value to render said amplifier ineffective, and means operated by signal impulses from said generator to change the potential on said terminal to a value rendering said amplifier operative to transmit a signal.

8. The combination set forth in claim 7 in which the means operated by signal impulses from the generator to change the potential on said terminal includes a condenser connected between said terminal and a point of fixed direct current potential, said condenser operating to prevent sudden changes in the direct current potential of said terminal.

9. The combination set forth in claim 7 in which the means operated by said signal impulses from said generator to change the potential on said terminal comprises a rectifier electron discharge device having an output circuit, and an input circuit connected to receive signal impulses from said generator, a relay having an energizing winding connected in the output circuit of said electron discharge device, a plurality of switches forming part of said relay and operable to disconnect said terminal from said means normally maintaining a potential thereon which renders said amplifier ineffective and to connect said terminal to a potential source of adjustable value capable of rendering said amplifier effective, thereby to produce a wide variety of tonal envelopes including percussion, organ and slow attack.

10. The combination set forth in claim 7 in which the means operated by signal impulses from said generator to change the potential on said terminal includes manually adjustable means to predetermine the value to which the potential on said terminal will be changed, and means for disconnecting said terminal from the means normally maintaining a potential on said terminal of a value to render said amplifier ineffective.

11. In an electrical musical instrument having a generator of electrical signal impulses, an amplifier for the output of said generator, a key controlled switch for rendering said generator operative, a terminal connected to said amplifier, the direct current potential of said terminal determining the degree of amplification effected by said amplifier, means normally applying a potential to said terminal approaching cutoff value thereby to render said amplifier relatively inef-

fective to transmit the signal from said generator, and a circuit completed by said switch to cause a change in the potential on said terminal to a value rendering said amplifier effective to transmit said generator signals.

12. In an electrical musical instrument having a generator of electrical signal impulses, an amplifier for the output of said generator, key controlled means for rendering said generator operative, a terminal connected to said amplifier, the direct current potential of said terminal determining the degree of amplification effected by said amplifier, means normally applying a cutoff potential to said terminal thereby to render said amplifier ineffective to transmit the signal from said generator, a vacuum tube relay operated by the signal produced by said generator, and circuits controlled by said relay for changing the potential on said terminal to a value rendering said amplifier effective.

13. In an electrical musical instrument, the combination of an oscillator having a resonant tuning circuit including an inductance and a plurality of condensers, a plurality of playing keys, a switch operated by each of said keys to connect selected capacitances in said oscillator tuning circuit to determine the resonant frequency thereof, an amplifier for the signals produced by said oscillator, a terminal the direct current potential of which determines the degree of amplification of said amplifier, and a voltage divider network for determining the direct current potential of said terminal, said voltage divider network including a circuit completed upon closure of any one of said switches and effective to change the direct current potential of said terminal to a value at which said amplifier is effective.

14. The combination set forth in claim 13 in which a condenser is connected between said terminal and a point of fixed direct current potential, said condenser being of sufficient value to prevent sudden changes in the direct current potential of said terminal.

15. The combination set forth in claim 13 in which a capacitance is connected between said terminal and a point of fixed direct current potential, and in which manually operable means are provided to change said capacitance, said capacitance being changeable through a range of values which will cause the potential on said terminal to change at a rate corresponding to either the fast or the slow attack of a musical tone.

16. In an electrical musical instrument having a master oscillator, a resonant circuit for determining the frequency of oscillation of said master oscillator, said resonant circuit including a relatively fixed inductance, a plurality of condensers, key controlled circuits for selectively connecting said condensers in said resonant circuit, a variable inductance, means for varying said variable inductance at a vibrato periodicity, and means for optionally rendering said variable inductance effective in said resonant circuit, said last named means including a compensating inductance capable of rendering the average total inductance of said resonant circuit substantially the same whether said variable inductance is rendered effective in said resonant circuit or not.

17. In an electrical musical instrument having an oscillator, a resonant circuit for determining the frequency of oscillation of said oscillator, said resonant circuit including a relatively fixed inductance and a capacitance, a variable inductance connected to said resonant circuit, means

for varying said variable inductance at a vibrato periodicity, and means for optionally rendering said variable inductance effective in said resonant circuit, said last named means including a compensating inductance capable of rendering the average total inductance of said resonant circuit substantially the same whether said variable inductance is rendered effective in said resonant circuit or not.

18. In an electrical musical instrument, the combination of an oscillator including a resonant tuning circuit determining the frequency of oscillation thereof, said tuning circuit comprising a plurality of capacitances, playing key operated means for selectively connecting said capacitances in said tuning circuit, a relatively fixed inductance, a variable inductance, switch means for effectively connecting said variable inductance in said tuning circuit, means for varying said variable inductance at a vibrato periodicity, and a compensating inductance associated with said variable inductance to render the average total effective inductance of said variable inductance and said compensating inductance substantially the same irrespective of the position of said switch means.

19. In an electrical musical instrument having an oscillator constituting a generator of electrical impulses of musical frequency, said oscillator having a resonant tuning circuit determining its frequency of oscillation, an inductance connected in said circuit, a vibrating reed, and a magnetic core secured to said reed and movable in the field of said inductance, thereby to vary the frequency of oscillation of said oscillator at a rate determined by the frequency of vibration of said reed.

20. The combination set forth in claim 19 in which the magnetic core consists of finely divided ferrous particles separated by an insulating binder.

21. In an electrical musical instrument having an output system, the combination of a normally non-operating oscillator having a frequency determining resonant circuit, a plurality of keys, circuits controlled by said keys to determine the resonant frequency of said resonant circuit and to cause said oscillator to oscillate, and means to couple said oscillator to said output circuit, said means comprising a relaxation apparatus including an electron discharge device, an input circuit for said device coupling said device to said oscillator, an output circuit for said device coupling said device to the output system of the instrument, and means providing bias to said device sufficient to prevent relaxation when said oscillator is not operating, but insufficient to prevent relaxation of said device when said oscillator is operating.

22. In an electrical musical instrument, the combination of an amplifier, a signal generator, means for tuning said generator throughout a musical frequency range of at least one octave, a coupling between said generator and said amplifier including a distorting relaxation device to follow the frequency of said generator, said relaxation device being biased to be non-operating except when a trip signal is supplied thereto, and keying means for causing said generator to supply a trip signal of sufficient amplitude to said relaxation device to control the frequency of relaxation thereof.

23. In an electrical musical instrument having an output system, the combination of a generator of electrical impulses, means for tuning said generator throughout a musical frequency range of at least one octave, means to couple said generator to the output system comprising a relaxation device, means to bias said device to render it non-self-oscillatory, a circuit for transmitting electrical impulses from said generator to said device, and key operated switch means for causing the transmission from said generator to said device through said circuit of electrical impulses of sufficient amplitude to trip said device and to control the frequency of relaxation thereof throughout the frequency range of said generator.

24. In an electrical musical instrument having an amplifying and electroacoustic translating system, said system including a terminal the direct current potential of which determines the intensity of the sound produced by the system, and having key controlled signal producing means for supplying electrical musical signals to said system, the combination of a relay, a circuit coupled to said signal producing means and maintaining said relay energized only during the time that a signal is being supplied to said system by said signal producing means, a circuit between said terminal and a point of fixed direct current potential normally maintaining said terminal at a potential at which said system is relatively ineffective to produce a sound, a resistance and reactance mesh associated with said terminal and having one or more junction points, means to adjust the direct current potential upon one or more of the junction points of said mesh, and means operated by said relay to render said mesh effective to control the potential upon said terminal, whereby said system will, during the time that said relay is energized, produce a sound having an intensity envelope of form determined by the adjustment of direct current potentials on the junction points of said mesh.

25. In an electrical musical instrument having an amplifying and electroacoustic translating system, said system including a terminal the direct current potential of which determines the intensity of the sound produced by the system, and having key controlled signal producing means for supplying electrical musical signals to said system, the combination of a relay, a circuit coupled to said signal producing means and maintaining said relay energized only during the time that a signal is being supplied to said system by said signal producing means, a circuit between said terminal and a point of fixed direct current potential normally maintaining said terminal at a potential at which said system is relatively ineffective to produce a sound, a resistance and capacity mesh associated with said terminal and having a plurality of junction points, means to adjust the direct current potential upon various junction points of said mesh, and means operated by said relay to render said mesh effective to control the potential upon said terminal, whereby said system will, during the time that said relay is energized, produce a sound having an intensity envelope of form determined by the adjustment of direct current potentials on the junction points of said mesh.

JOHN M. HANERT.
